(57) **CLAIM**

The ornamental design for an automotive tissue valet, as shown and described.

DESCRIPTION

FIG. 1 is a three-dimensional isometric view of a automotive tissue valet shown in a typical environment of a car seat, shown in dashed lines.

FIG. 2 is an isometric view shown from a frontal view.

FIG. 3 is an isometric view shown from a rear view with a partially opened top portion.

FIG. 4 is a front elevational view thereof.

FIG. 5 is a rear elevational view thereof.

FIG. 6 is a left side elevational view thereof.

FIG. 7 is a right side elevational view thereof.

FIG. 8 is a top plan view thereof; and,

FIG. 9 is a bottom plan view thereof.

The broken lines shown in the figures represent portions of the automotive tissue valet that form no part of the claimed design.
